Primary Examiner—T. Chase Nelson*Assistant Examiner*—Mark Cavanna(74) *Attorney, Agent, or Firm*—Tara M. Hartman; Barnes & Thornburg, LLP(57) **CLAIM**

We claim the ornamental design for a kickplate, as shown and described.

DESCRIPTION

FIG. 1 is a front perspective view of a kickplate showing our new design;

FIG. 2 is a front elevational view thereof; and,

FIG. 3 is a bottom plan view thereof.

The rear elevational, side opposite the side shown in FIG. 1, and the portions of the top not shown in FIG. 1 form no part of the claimed design.

The broken lines are included for the purpose of illustrating portions of environmental elements around the kickplate and forms no part of the claimed design.
